UNITED STATES PATENT OFFICE

2,627,638

TERMINAL FOR WRISTBANDS FOR WATCHES

Alfred Pinson, Stamford, Conn., assignor to Apex Accessories Co., Inc., Greenwich, Conn.

Application July 30, 1951, Serial No. 239,249

4 Claims. (Cl. 24—235)

1

My invention relates to watch band terminals for wrist bands for watches, and the object is to provide a terminal that will secure to the band a watch provided with rings or eyelets for attachment.

Another object of the invention is to provide the band with terminals having two relatively movable latching members, both actuated by the same means.

In the appended drawing, forming part of this application,

Figure 1 is a section on line 1—1, Figure 4, showing the terminal in locked position;

Figure 2 is a similar section on line 2—2, Figure 3, showing the terminal open;

Figure 3 is a section on line 3—3, Figure 1, in the direction of the arrow on the top of the figure;

Figure 4 is a section on line 4—4 in the direction of the arrow at the bottom of the figure;

Figure 5 is an edge elevation of the liner;

Figure 6 is a plan of the movable arm; and

Figure 7 is an edge elevation of same.

Referring to the drawings, a liner 10 formed of a plate having a semi-circular edge 11, from which edge a fixed arm 12 extends co-planar with the rest of the plate but disposed towards one side. The arm 12 on the inner face and near the end thereof and towards the inward edge has a flange 13 rising at right angles to the plane of the plate. Preferably the outer surface of said flange 13 is flush with the edge from which it rises.

Pivoted on the inner face of the liner 10 with one end thereof is an L-shaped lever 14. The pivoted leg 15 of the lever is within the area of the arm 12 except of the pivot 16, which is located near the junction of the arm with the semi-circular edge 11. The other leg 17 of the L-shaped lever extends through an opening 18 in the flange 13. To properly centralize the opening 18 with the leg 17, a spacer 19 is provided between the end of leg 15 and the liner 10 at the pivot 16.

The liner 10 has a collar 20 rising from the inner face thereof and concentric with the semi-circular edge 11 of the liner 10. See Figures 3, 4, and 5. An arm 21 having the contour of the fixed arm 12 is provided with an extension 22 offset laterally of the arm 21 to permit said extension to lie on the outer face of the liner 10 with the arm 21 being directly opposite and co-planar with the fixed arm of the liner. See Figures 6 and 7.

The extension 22 has a bore 23 of the same diameter as the bore of the collar 20 to accommodate a rivet 24, whereby the arm 21 is con-

nected pivotally to the liner 10 to swing to and from the fixed arm 12 along the semi-circular edge 11. The swinging movement of the arm 21 on the liner 10 is limited by the engagement of a lug 25 rising from the extension 22 of the arm 21 with a slot 26 in the liner 10, as best seen in Figures 1, 2 and 7.

The edge of the arm 21 proximate to the fixed arm 12 has a flange 27 similar to flange 13 on the arm 12 and in alignment therewith. The flange 27 is provided with an aperture 28 to receive the end 29 of the leg 17 of the L-shaped lever 14. This end 29 has a notch 29' adapted to engage the inner face of the flange 27 of the swinging arm 21.

Mounted on the outside of the collar 20 is a helical spring 30, one end 31 of which engages the lug 25 of the pivoted arm 21, while the other end 32 of the spring 30 engages a notch 33 in the leg 15 of the L-shaped lever 14. The tendency of the spring 30 is normally to move the L-lever 14 and the pivoted arm 21 apart but prevented from so doing in the closed position of the terminal by the latching of the movable arm 21 with the L-lever 14.

The liner 10 with its fixed arm 12 receives a cover or top 34, which cover on the open side has notches (not shown) to engage and rest on shoulders 35 (see Figure 5), and the liner 10 also has depressions 36, see Figures 1 and 2, to accommodate the tongues (not shown) by means of which the cover is locked to the liner. A cover 37 is also provided for the arm 21, that is to say, that portion of the arm which extends past the curved edge of the liner 10. Said arm has at the end thereof shoulders 38 for engaging the corresponding notch in the open end of the cover 37. The arm 21 has also depressions 39 to house the tongues of the cover 37 by which it is locked to the arm. These tongues are not shown in the drawing.

The liner 10 on the inner face thereof and near the straight edges extending from the semi-circular portion thereof is provided with ears 40, substantially in alignment on an axis that is parallel to the straight edge 41 of the liner. The aperture 42 in the ears forms means for attaching the terminal to a band.

The terminal in closed position has the two arms 12 and 21 spanned by the leg 17 of the L-lever 14. The notch 29' at the end 29 of the leg 17 is engaged by the flange 27 through the aperture 28; see Figure 1. To open the terminal either to remove or to attach a watch to the terminal, the leg 17 of the L-lever is pressed to move

against the resistance of the spring 30, thus pivoting the L-lever 14 on the pivot 16 to disengage notched end 29 of leg 17 from flange 27 of the swinging arm 21, thereby permitting the swinging arm 21 and the L-lever 14 to separate. See Figure 2. In said figure the L-lever is shown in position when the notched end 29 has just released the arm 21 by the disengagement of said notched end 29 of the leg 17 from the flange 27. The movement of the L-lever on the pivot 16 away from the swinging arm 21 is limited by the engagement of the leg 17 with the edge of the aperture 18 in the flange 13 near the end of the fixed arm 12.

To span the gap between the fixed arm 12 and the swinging arm 21 in closing the terminal, the arm 21 is moved to engage the notched end 29 of the leg 17 of the L-lever 14, bringing the apertured flange 27 of the pivoted arm 21 into engagement with the notched end 29 of the leg 17, which causes the said L-lever to move on its pivot 16 and bring the notch 29' in latching position with the said flange 27 of the swinging arm.

I claim:

1. A band terminal comprising a liner having a fixed arm to one side thereof and co-planar with the liner, a second arm pivoted to the liner to swing to and from the fixed arm and co-planar with said fixed arm, means for limiting the movement of the pivoted arm on the liner and providing a gap between the arms, a latch pivoted on the liner and extending from the fixed arm towards the pivoted arm, a helical spring mounted on the liner and having its ends connected respectively to the latch and to the pivoted arm, said spring normally tending to move said latch and arm apart, said latch and pivoted arm having coupling means adapted to interlock by the action of said spring, whereby the gap between the arms is spanned by said latch, said latch being adapted to disengage the pivoted arm when it is moved against the resistance of the spring, a cover for the liner with its fixed arm, and a cover for the pivoted arm.

2. A band terminal comprising a liner having a fixed arm to one side and coplanar with the liner, a second arm pivoted to the liner and coplanar with the fixed arm, means carried by the fixed arm and engaging the liner to limit the movement of said pivoted arm on the liner and to provide a gap between the said arms, a latch in the shape of an L having one leg thereof pivoted on the liner while the other leg extends from the fixed arm to the movable arm, said second leg having means for engaging the movable arm, a helical spring mounted on the liner with one end thereof engaging the pivoted leg of the latch, the other leg of said spring engaging the means for limiting the movement of the pivoted

5 15 20 30 35 40 45 50 55 60

arm, a cover for said liner with the fixed arm, and a cover for the pivoted arm.

3. A band terminal comprising a liner having a fixed arm to one side thereof and co-planar with the liner, a second arm pivoted to the liner to swing to and from the fixed arm and co-planar with said fixed arm, means for limiting the movement of said pivoted arm on the liner and providing a gap between the arms, an L-shaped latch having one leg thereof pivoted on the liner with the other leg extending from the fixed arm to the movable arm, said second leg having means for engaging the movable arm, a helical spring mounted on the liner and co-axial with the pivot of the movable arm, said spring having one end thereof engaging the pivoted leg of the latch, while the other end of said spring engages the means for limiting the movement of the pivoted arm, said spring normally tending to move the pivoted arm and the latch apart, a cover for said liner with the arm, and a cover for the pivoted arm.

4. A band terminal comprising a liner having a fixed arm to one side thereof and co-planar with the liner, a second arm pivoted to the liner to swing to and from the fixed arm and co-planar with said fixed arm, each of said arms having a rising flange at the proximate edges of the arms and near the ends thereof, said flanges rising substantially at right angles to the inner face of the liner, means for limiting the movement of the pivoted arm on the liner and providing a gap between the flanges, an L-shaped latch having one leg thereof pivoted on the inner face of the liner with the other leg extending from the fixed arm through its flange to the movable arm, said second leg of the latch having means for engaging the flange of the movable lever, a helical spring mounted on the inner face of the liner co-axial with the pivot of said movable lever, said spring having one end thereof engaging the pivoted leg of the latch, while the other leg of said spring engages the means for limiting the movement of the pivoted arm, the normal tendency of said spring is to move said pivoted arm and latch apart, a cover for said liner with the arm, and a cover for the pivoted arm.

ALFRED PINSON.
